BLOWER IMPELLER

Johann Fullemann, Washington, D. C.

Original application December 17, 1940, Serial No. 370,553. Divided and this application May 13, 1943, Serial No. 486,887

4 Claims. (Cl. 230—134)

This application is a division of my pending application, Serial No. 370,553, for "Blower impellers and methods of manufacturing same," filed December 17, 1940.

This invention relates to improvements in centrifugal gas blowers, and more particularly to impellers of the closed type, of a construction which is particularly adaptable for being produced by die-shaping, that is, die-casting or drop-forging. By "closed type" impellers is meant impellers in which the generally radially disposed blower vanes are disposed between a pair of disc-like plates at their sides so that the gas passages formed by the vanes and plates and which extend in generally radial directions are open only at their inner and outer ends.

The closed type of impellers is recognized as being more efficient aerodynamically than "open" type impellers, that is, the type having at least one side of the air passages open; but, on the other hand, the closed type of impeller has presented certain manufacturing problems and difficulties which have to some extent retarded their adoption.

It has been proposed to make impellers of the closed type by casting in one piece and, with certain refinements of construction, this system of manufacture has proved successful, but ordinary casting operations involve comparatively greater labor and time, and for quantity production it is more desirable to find structures in which drop-forging or die-casting can be used in place of ordinary casting.

The present invention has for an object to provide a closed type impeller adapted to be produced in two principal parts by permanent mold operations, that is, by die-shaping, such as drop-forging or die-casting, operations and which parts can then be readily brought into condition to be effectively joined together into an assembled impeller.

A further object of this invention is to provide a closed type impeller in which two parts produced by die-shaping operations are assembled with locking shoulders adapted to transmit the centrifugal forces therebetween and held together in engaging relation by securing means extending through the blades and through the side plates.

Another object of this invention is to provide a closed type impeller having vanes of fluid foil cross-sectional shape, considered in a plane transverse to the axis of rotation.

Further objects and advantages of the invention will be apparent from the following de-

tailed description of the method and the accompanying drawings which illustrate an embodiment of the invention.

In the drawings:

5 Fig. 1 is an axial sectional view on the line I—I of Fig. 2 of a centrifugal blower having a closed type impeller composed primarily of two die-shaped parts joined together;

10 Fig. 2 is a sectional view of the impeller on the line II—II of Fig. 1 illustrating the cross-sectional shape of the vanes; and

Fig. 3 is a cross-sectional view of part of the impeller on the line III—III of Fig. 1.

15 In Fig. 1 of the drawings a centrifugal blower casing is designated by numeral 1. The casing may be of the general shape of a volute and is provided with a gas inlet opening 2 at one side and an opening 3 for the impeller drive shaft 4 at the other side. The impeller hub 6 is mounted 20 on the drive shaft 4. This hub forms the central portion of one main part of the impeller which comprises, in addition to the hub, a plate 7 extending outwardly and parts 8 of the vanes 9 extending approximately at right angles to said plate.

25 The other main part 10 of the impeller comprises a ring-shaped plate 11 having a central opening 12 and other parts 13 of impeller vanes corresponding in position and registering with 30 the respectively corresponding parts 8 of vanes 9. It is apparent from Fig. 1 that the plates 7 and 11 close the sides of the gas passages 14 between the vanes so that only the inner and outer ends thereof are open. The impeller is 35 therefore of the closed type.

From Fig. 1 will also be seen that the two parts

38 and 13 of the impeller vanes have engaging shoulders 16 and 17 which resist the tendency of the part 10 of the impeller to be distorted out- 40 wardly under the strong influence of centrifugal force at high speed. The two parts of the im- 45 peller are held together in locking engagement by securing means which may comprise bolts or rivets 18 which pass through openings 19 in the plates and vanes at radially intermediate points where the vanes are of comparatively greater thickness. At the points where the rivets pass through the plates 7 and 11 the plates are of in- 50 creased thickness in order to be better able to

55 carry the stress applied by the rivets. This thickening is conveniently obtained by providing a ring-like flange or rim 15 on plate 7 having a shoulder surface which cooperates with a labyrinth packing 21, which seals between plate 7 and casing 1, and the thick portion 20 of plate 11.

also has a shoulder which cooperates with another packing 28.

In order that the vanes shall have sufficient thickness to accommodate the bolts and to resist the strong centrifugal forces without greatly reducing the aerodynamic efficiency of the impeller or causing undesirable whistling noise in operation, the vanes are given fluid foil shape in the direction of flow of the gas. This fluid foil cross-sectional shape is clearly apparent from Fig. 2 of the drawings, from which it can be seen that the inner and outer edges of the vanes are comparatively thin and rounded off while the central parts are thicker and of sufficient thickness to allow the rivets 18 to pass therethrough. The surfaces of the rounded-off inner and outer edges pass over smoothly to the surfaces of the central parts so as to avoid impairment of aerodynamic efficiency and minimize noise in operation.

Another feature of the shape of the vanes is that their thickness is progressively greater from the centers toward their lateral edges, as is apparent from Fig. 3. The most important purpose of this feature is to provide the necessary draft to enable removal of the vanes from the dies in their production by die-shaping operations.

The present construction is particularly well adapted for production of impellers in large quantities, that is, such quantities as would be required for small-size impellers for use in turbochargers or supercharging comparatively small internal combustion engines. By reason of the smooth surfaces obtained by die-shaping operations, compared with the rough surfaces obtained by ordinary sand casting methods, the provision of a construction which is adaptable for die-shaping is of extreme importance. This eliminates a large amount of finishing and polishing after the casting operation, while at the same time providing impeller vanes which are sufficiently smooth to give good aerodynamic efficiency.

Compared with other constructions, the present construction has the advantage of great simplicity and speed of production, yet gives impellers of great strength and dependability without material sacrifice in efficiency over impellers made according to other constructions and by more laborious and time-consuming methods.

I claim:

1. An impeller of the closed type for rotary centrifugal gas blowers comprising a pair of plates each having a plurality of blower vane parts formed on a side wall thereof, said vane parts being located on said plates in registering pairs, the corresponding surfaces thereof fitting together exactly and having interengaging shoulders facing inwardly and outwardly respectively for transfer of radial forces, said plates and vanes having openings extending therethrough substantially in the direction of the axis of rotation of the impeller, and securing means extending through said openings.

2. In a centrifugal blower, a casing, a rotary impeller of the closed type, said impeller comprising a pair of plates each having parts of impeller vanes formed on one side in position to register with corresponding vane parts of the other plate, the corresponding vane parts fitting together exactly, the sides of the gas passages formed between the vanes being closed by said plates and one of said plates having a central opening serving as an inlet for gas to said passages, said plates having circularly extending portions of greater thickness than their normal thickness extending around said plates at positions opposite the middle portions of the vane parts, the middle portions of said vanes and said thicker portions of said plates being provided with openings extending in the general direction of the axis of rotation of the impeller, and securing means extending through said openings, said thicker portions 20 of said plates having cylindrical outer surfaces and labyrinth packings engaging said cylindrical surfaces and the casing and sealing therebetween.

3. An impeller of the closed type for rotary centrifugal blowers comprising a pair of plates each having parts of impeller vanes formed on one side in position to register with corresponding vane parts of the other plate, the corresponding vane parts fitting together exactly, the sides of the gas passages formed between the vanes being closed by said plates and one of said plates having a central opening serving as an inlet for gas to said passages, some of the corresponding vane parts having registering openings extending therethrough and through the plates in the direction of the axis of rotation of the impeller, and securing means extending through said openings, said vane parts being thicker at the lateral ends adjacent the plates than at the centers and being thicker at their radially intermediate portions than toward their inner and outer edges.

4. An impeller of the closed type for rotary centrifugal blowers comprising a pair of plates each having parts of impeller vanes formed on one side in position to register with corresponding vane parts of the other plate, the corresponding vane parts fitting together exactly, the sides of the gas passages formed between the vanes being closed by said plates and one of said plates having a central opening serving as an inlet for gas to said passages, and means for securing the edges of said vane parts together in assembled relation to form the complete vanes, said vanes having substantially straight outwardly extending axes, the surfaces of said vanes being free of concave surfaces, said vane parts being thicker at the lateral ends adjacent the plates than at the centers and being thicker at their radially intermediate portions than toward their inner and outer edges.

JOHANN FULLEMANN.
